UNITED STATES PATENT OFFICE.

BYRON DURLIN, OF ELDRED, PENNSYLVANIA, ASSIGNOR OF ONE-HALF TO
CARL D. MARSH, OF ELDRED, PENNSYLVANIA.

PERMUTATION-LOCK.

SPECIFICATION forming part of Letters Patent No. 735,225, dated August 4, 1903.

Application filed June 27, 1902. Serial No. 113,430. (No model.)

To all whom it may concern:

Be it known that I, BYRON DURLIN, a citizen of the United States, residing at Eldred, in the county of McKean and State of Pennsylvania, have invented a new and useful Permutation-Lock, of which the following is a specification.

This invention relates generally to permutation-locks, and particularly to that class employed upon post-office letter-boxes.

The object of the invention is in a simple, ready, feasible, and thoroughly practical manner to effect shifting of the tumblers in both the act of opening and of closing the door, thereby at once to prevent a bystander from ascertaining the combination, and to render manual operation of the combination-indicators unnecessary when the door is shut and locked, so that if the box-renter fails to shift the tumblers, as is necessary with locks of this character in general use, it will be a matter of no moment, as this will have been automatically effected by the attachment constituting the gist of the present invention.

A further object is to accomplish the results above specified without any change in the structural arrangement of the lock, thereby rendering it easy to apply the device of this invention to a lock already in use with but little labor and at a slight cost.

With these and other objects in view, as will appear as the nature of the invention is better understood, the same consists, generally stated, in combining with the lock-tumblers a reciprocatory element provided with means for engaging the tumblers, and an automatically-operating device coacting with the said element to cause one of the combination-indicators to be shifted when the door is opened, the other combination-indicator being shifted when the door is closed by coaction between the reciprocatory element and a part of the door frame or casing.

The invention consists, further, in the novel details of construction of an automatically-operating lock-combination shifting device, as will be hereinafter fully described and claimed.

In the accompanying drawings, forming a part of this specification, and in which like numerals of reference indicate corresponding

parts, there is illustrated one form of embodiment of the invention capable of carrying the same into practical operation, it being understood that the elements therein exhibited may be varied or changed as to shape, proportion, and exact manner of assemblage without departing from the spirit thereof.

In the drawings, Figure 1 is a view in elevation, partly in section, of a letter-box equipped with the device of the present invention, the door being locked. Fig. 2 is a similar view showing the door open. Fig. 3 is a view in vertical transverse section through the door and lock. Fig. 4 is a detached detail view in perspective of the tumbler-shifting device constituting the present invention.

Referring to the drawings, 1 designates the casing or door-frame of an ordinary letter-box, and 2 the door, and as these parts may be of the usual or any preferred construction detailed illustration thereof is deemed unnecessary. Secured to the door is a lock 3, of the permutation type in common use in many post-offices. In this instance the lock is shown as provided with two peripherally-notched tumblers 4 and 5; but it is to be understood that the invention is adaptable in connection with a lock having a greater number of tumblers. The tumbler 4 has connected with it a shank 6, which extends to the front of the door and carries one of the combination-indicators, in this instance a knob 7 and a pointer 8, and the tumbler 5 has associated with it the other combination-indicator, consisting of a dial 9, with which is associated an operating-stud 10. The general description here given of the lock and combination elements is deemed to be sufficient to render clear an understanding of the case, particularly as the exact manner of construction of these parts has nothing to do with the present invention.

The novelty of the invention resides in a tumbler-shifting device which is rendered operable on both movements of the door—that is to say, when it is opened and closed. This device, which is illustrated in detail in Fig. 4, comprises a reciprocatory member 11, provided with a curved terminal 12, adapted to engage with one of the walls of a recess 13

in the door-casing, and intermediate of its ends with two oppositely-disposed downwardly-extending tumbler-engaging dogs 14 and 15, the former of which coacts with the tumbler of the dial and the latter with the tumbler of the pointer. Adjacent to the arm 12 the member 11 is provided with an orifice 16, through which projects the reduced upper end of a spring 17, which is held in operative position with relation to the member, in this instance by being secured between one edge of the glass panel 18 and two panel-keepers 19, as clearly shown in Fig. 1. It is to be understood, however, that the invention is not to be limited to this precise manner of securing the said spring, as the same result may be otherwise attained and still be within the scope of the invention. The function of the spring is to hold the reciprocatory member in the position shown in Fig. 2 and the function of the wall 20 of the recess 13 to hold the said member in the position shown in Fig. 1.

The tumbler-engaging dogs 14 and 15 are in this instance shown as integral with the member 11 and are produced by cutting a slot 21 in the member and then severing one wall of the slot and bending the two arms thus formed downward to present dogs; but it is to be understood that if preferred the dogs may be made as separate elements and secured to the member 11 and still be within the scope of the invention. The member 11 is held in operative position with relation to the tumblers by being passed between the upper side flange of the lock-casing 23 and its end flanges, the free terminal of the element being upturned, as at 24, to present a stop to limit the longitudinal movement of the member.

The operation of the device is as follows: The tumblers having been actuated in the usual manner to bring the gates thereof into alignment with the locking-bolt 25, the bolt-operating button or handle 26 is turned or moved to force the latch out of engagement with the strike-plate 27. As soon as the door starts to open the spring 17 begins to draw back the member 11, thereby causing the dog 15 to engage with the notches of the pointer-tumbler and effect shifting of the pointer away from the number on the dial to which it was moved. When the door is closed, the terminal 12 of the spring is brought into engagement with the wall 20 of the recess, thus moving the member laterally and causing the dog 14 to engage with the notches of the dial-tumbler and effect shifting of the dial away from the indicating-mark on the door to which it was moved. It will thus be seen that the necessity of any attention on the part of the box-renter to effect shifting of the combination for the purposes defined is rendered entirely unnecessary, thereby positively obviating all danger of the combination becoming known to an unauthorized person, or of loss of mail-matter, which might result were the box left unlocked.

It will of course be understood that various changes of the proportions of the parts of the device shown and also the manner in which it is associated with the lock may be resorted to without departing from the spirit of the invention, the broad underlying feature of which is the provision of means actuated by the opening and closing of the door to effect shifting of the tumblers.

While the invention is herein described as employed in connection with a letter-box door, it will be obvious that it may be employed in any position where its use will be found advantageous or desirable.

Having thus fully described my invention, what I claim as new, and desire to secure by Letters Patent, is—

1. In a lock, the combination with the tumblers, of a reciprocatory device carrying means adapted alternately to engage and shift the tumblers.

2. In a lock, the combination with the tumblers, of an element carrying tumbler-shifting devices, and means for reciprocating the said element to cause the said devices alternately to shift a tumbler.

3. In a lock, the combination with the tumblers, of an element provided with tumbler-shifting means, and an automatically-operating device coacting with the said element to cause the said means to shift one of the tumblers when the door carrying the lock is opened, and means to cause the said element to shift another tumbler when the door is closed.

4. The combination with a door carrying a lock provided with peripherally-notched tumblers, of a slide-plate actuated by the opening and closing of the door, and means carried by the plate and operating alternately to effect shifting of a tumbler.

5. The combination with a lock provided with peripherally-notched tumblers, of a reciprocatory element provided with means for engaging said notches, and an automatically-operating device coacting with the reciprocatory element to cause it, when the door is opened, to shift one of the tumblers, and means coacting with the said element to cause it, when the door is closed, to shift another tumbler.

6. The combination with a door carrying a lock provided with peripherally-notched tumblers, of a reciprocatory element having means to engage the tumblers, an automatically-operating device coacting with the said element to retract it when the door is opened, thus to shift one of the tumblers, and a projection on the door-casing to engage the element when the door is closed to return it to its normal position and thereby shift another tumbler.

7. The combination with a lock provided with peripherally-notched tumblers, of a reciprocatory element carrying oppositely-flexed spring-dogs arranged in the path of the tumblers, the said element being provided

with a curved terminal, a spring carried by the door with which the lock is associated and operating, when the door is opened to move the element in one direction, and a projection 5 on the door-casing adapted to engage the curved terminal to move the element in the opposite direction when the door is closed.

In testimony that I claim the foregoing as my own I have hereto affixed my signature in the presence of two witnesses.
